[57] CLAIM

The ornamental design for a pull, as shown.

DESCRIPTION

FIG. 1 is a front view of a pull which embodies the principles of my new design;

FIG. 2 is a bottom view of my pull;

FIG. 3 is an end view of the pull;

FIG. 4 is a fragmentary sectional view taken along the line 4—4 in FIG. 1; and

FIG. 5 is a sectional view taken along the line 5—5 in FIG. 1.

UNITED STATES PATENT OFFICE
CERTIFICATE OF CORRECTION

Patent No. D-243,661 Dated March 15, 1977

Inventor(s) HUBERT DOLLNER

It is certified that error appears in the above-identified patent and that said Letters Patent are hereby corrected as shown below:

The correct spelling of the inventor's last name
should read DOLLNER

Signed and Sealed this

Twenty-second Day of November 1977
